UNITED STATES PATENT OFFICE.

HOMER N. MOTSINGER, OF LA FAYETTE, INDIANA.

CARBURETER.

1,224,489.

Specification of Letters Patent.

Patented May 1, 1917.

Application filed August 13, 1915. Serial No. 45,331.

To all whom it may concern:

Be it known that I, HOMER N. MOTSINGER, a citizen of the United States, residing at La Fayette, in the county of Tippecanoe and State of Indiana, have invented a new and useful Improvement in Carbureters, of which the following is a specification.

My invention relates to improvements in carbureters and my object is to provide a novel design of carbureter particularly suited for use on internal combustion engines which operate under considerable variations of speed and load, such for instance as automobile engines. The carburetion requirements of such engines are peculiarly difficult in that the demand of the engine for gas is subject to the widest and most sudden fluctuations, and it is my primary purpose therefore to provide a carbureter of such construction as to be capable of efficient action under these conditions.

In Figure 1 of the accompanying drawing I have illustrated in longitudinal section a form of carbureter embodying the principles of my invention, and from this drawing, in connection with the following description, it will be possible to fully comprehend these principles and one mode in which they may be applied in carrying the invention into effect. Fig. 2 of the drawing illustrates a modified construction of the valve-loading mechanism.

The primary structural element of a carbureter embodying my invention consists of an air conduit or passageway member opening at one end to the outer atmosphere and at the other end discharging into the intake passage of the engine. Such a conduit is illustrated in the drawing (Fig. 1) as a tubular casting 1, the end 2 of which is provided with a flange 3 by which attachment to the engine may be effected, while the opposite end 4 is provided in its upper face with an aperture 5 opening to the atmosphere. The tubular member 1 is preferably of Venturi-tube form as shown, consisting of a contracted throat 6 with a relatively quick-tapered inlet portion leading from the end 4 and a relatively long-tapered outlet portion leading to the end 2. The latter end is preferably cylindrical to cooperate with an ordinary butterfly throttle valve 7, while the end 4 may be of box-like form as shown, in order to provide a flat surface surrounding the aperture 5.

The second structural element of my car-

bureter consists of an automatically operating loaded valve controlling the admission of air to the outer end of the air conduit or passageway member. In the embodiment of the invention which I have illustrated, this valve consists of a screw-threaded cage or seat-ring 8 which is mounted within the aperture 5 and has a flange 9 resting on the flat upper face of the box-like end 4, and a puppet or mushroom valve 10 the head of which normally seats against the seat-ring 8 and the stem of which is guided by a hub carried upon the spider arms 11 of the seat-ring. The valve 10 is loaded by means of a weight 12 mounted on a lever 13 which is pivoted at 14, in a suitable pivot bearing carried by the seat-ring member 8, and has its opposite end forked to embrace the stem of the valve 10, the forked ends being slotted to engage a pin 15 mounted on the valve. By this construction the weighted lever 13 urges the valve toward its seat with an approximately constant force, so that in the operation of the carbureter the pressure within the end 4 of the conduit 1 will at all times remain approximately the same, i. e., below atmospheric pressure by an amount determined by the effective force exerted on the valve stem by the weighted lever 13. This force may readily be varied either by removing the weight 12 and substituting a lighter or heavier piece therefor, or by adjusting the weight along the lever 13, which latter result may readily be effected by screw-threading the end of the lever 13 and fixing the weight 12 thereon by adjustable nuts 16 as shown in the drawing, so that the constant sub-atmospheric pressure or vacuum maintained during normal operation of the carbureter in the chambered end 4 thereof may be accurately fixed to obtain the best results.

In order to steady the action of the valve 10 it may be advisable under certain circumstances to apply dampening means thereto. Such means is shown in the drawing as a conventional dash-pot arrangement, the cylinder 17 being carried by arms formed on the seat-ring 8, and the piston comprising a disk 18 detachably mounted upon the extended end of the valve stem.

In Fig. 2 I have shown a modified construction of the valve-loading means. In this construction a pair of tension springs 30 are caught at their inner ends by a slotted connector 31 the slot of which embraces

the valve stem, and are fastened to swivels 32 carried by adjustment screws 33 at their outer ends. The screws 33 are mounted in blocks 34 which form corner members of a parallel linkage 35, the other pair of corner members (36) having bores to receive the valve stem. The latter carries a nut 37 which contacts with the top corner member (36) of the parallel linkage. It will be understood that as the valve opens under suction the parallel linkage will be flattened out, against the tension of the springs 30, and that by reason of the changing angle of the links, which in effect constitute opposed toggle-joints, the effective load on the valve may be kept almost constant throughout its range of movement. The value of the load may be adjusted by means of the screws 33, by increasing or decreasing the normal tension of the springs 30.

The third structural element of a carbureter embodying my invention consists of a relatively small air-intake conduit entering the large conduit 1 intermediate the length of the latter and having free communication with the atmosphere at its outer end. In the drawing this element is shown as a Venturi-tube 19 of the same general construction and proportions as the large tube 1 and entering the latter at an angle of 45° to the axis thereof, the discharge end of the tube 19 being slightly behind the throat.

The fourth structural element of my carbureter consists of a fuel nozzle opening into the small Venturi-tube 19 intermediate its length. This nozzle is shown on the drawing at 20, entering the tube 19 at an angle of 45° and terminating in the same position with reference to the throat of the tube 19 as the discharge end of the latter occupies with reference to the throat of the tube 1. The nozzle 20 may be controlled as by a needle-point valve 21 screwthreaded in the wall of the conduit 1 and having a knurled adjustment head 22 accessible from the top of the carbureter.

The last structural essential of my carbureter is a means for supplying fuel to the nozzle 20. Such means is shown as a constant-level float-controlled supply-chamber 22. The construction and operation of such devices is well known and forms no part of my invention. It need only be said therefore that the fuel supply is constantly maintained at a pre-determined level within the chamber 22, and it is immaterial to my invention what means be employed to this end, or what the level of the fuel may be, so long as it is not high enough to escape by gravity from the nozzle aperture nor low enough to require an inordinately great suction on vacuum to lift it to the nozzle aperture.

The several structural elements of my carbureter having been arranged in the manner described, and the carbureter secured to the intake member of an internal combustion

engine or like gas-consuming machine, it will function in the following manner.

When the demand upon the carbureter for gas is at a minimum, as in the cranking or idling of an internal combustion engine, the valve 10 may remain seated the entire air supply entering through the tube 19 or the valve 10 may open very slightly to admit a small quantity of air. As the air entering the tube 19 approaches the throat of the latter it will, by reason of its velocity, exert a strong "aspirating" effect upon the nozzle 20, and will draw the fuel up within the same and cause it to spray outward into the passing air stream, whereby the latter becomes impregnated with the atomized or volatilized fuel and is rendered explosive or combustible. The "mixture" or carbureted air will issue from the tube 19 and pass through the outlet end of the tube 1 and thence to the engine. The proportion of fuel contained in the air may be regulated by adjusting the load upon the valve 10, whereby the vacuum within the carbureter may be varied, until the best results are obtained, such possibility of adjustment being particularly useful in internal combustion engines by reason of the fact that air leaks frequently exist around the valves and intake pipe connections of the engine, which leaks may dilute the entering stream of carbureted air to such an extent that it becomes desirable to compensate for the dilution by initially over-carbureting.

As the demand of the engine for gas rises substantially above this minimum value, the valve 10 will open further admitting a substantial quantity of air to the chamber 4. This air in passing through the tube 1 will exert an "aspirating" effect upon the discharge end of the tube 19 which is cumulative upon the static vacuum effect, whereby the velocity of the air passing inward through the latter will be increased, and by consequence, the "aspirating" effect upon the nozzle 20 will be increased, whereby an increasing percentage of fuel will be delivered from the nozzle, such increasing percentage or over-carburetion serving to compensate for the dilution effected by the air entering through the valve 10.

As the demand for gas increases still further the valve 10 will open still wider, the vacuum within the chamber 4 being thereby maintained at its proper constant value, and the increased "aspirating" effect due to the higher velocity through the tube 1 being relied upon to increase the effective delivery of fuel from the nozzle 20 to compensate for the increased volume of diluting air, the needle valve being adjusted to obtain the best results.

From the foregoing it will be seen that my carbureter is characterized by the following principles of operation: First, it may be de-

fined as a constant vacuum instrument, in that the static or absolute vacuum within the body thereof is designed to remain at an approximately constant value throughout the 5 range of action, being so maintained by the loaded valve. (It will be understood of course that the same effective results may be obtained with various other forms of valves and loading means). Second, the increased 10 effective fuel delivery which compensates for the diluting air is supplied by a cumulative "aspirating" effect of the tubes 1 and 19 and wholly without material change in the static or absolute vacuum.

15 While I have particularly described a specific construction which I find well adapted to perform the objects of my invention, it is to be understood that this description is illustrative only and for the purpose of rendering my invention more clear, but I do not regard the invention as limited to the details of construction and arrangement shown, nor to any of them, except in so far as I have included them within the terms of the following claim, in which it is my intention to 20 25

claim all novelty inherent in the device as broadly as is permissible in view of the prior art.

What I claim is:

In a carbureter and in combination, a relatively large Venturi-tube having its exit end adapted to be connected to an engine to be supplied and having an air admission port in its entrance end, a constantly loaded automatically operating valve controlling the admission of air through the said port, a relatively small Venturi-tube having its entrance end open to the atmosphere and its exit end discharging into the said larger Venturi-tube at an angle to the axis thereof and at a point behind the throat of the same, a fuel nozzle discharging into said smaller Venturi-tube at an angle to the axis thereof and at a point behind the throat of the same, and a constant pressure means for supplying fuel to the said nozzle.

HOMER N. MOTSINGER.
